UNITED STATES PATENT OFFICE.

LOUIS F. FLIPSE, OF SHEBOYGAN, WISCONSIN.

PACKING-PAD.

No. 901,334.

Specification of Letters Patent.

Patented Oct. 20, 1908.

Application filed November 4, 1907. Serial No. 400,545.

To all whom it may concern:

Be it known that I, LOUIS F. FLIPSE, a citizen of the United States, residing at Sheboygan, county of Sheboygan, and State 5 of Wisconsin, have invented certain new and useful Improvements in Packing-Pads, of which I do declare the following to be a full, clear, and exact description, reference being had to the accompanying drawings, 10 forming part of this specification.

The present invention has for its object to provide an improved construction of cushioning pad which, while more particularly designed for the packing of fragile 15 articles such as glass bottles, jars and the like, will be found applicable for use in other situations.

The invention consists in the various novel 20 features of construction hereinafter described, illustrated in the accompanying drawings and particularly pointed out in the claims at the end of this specification.

Figure 1 is a perspective view of the pad embodying my invention, the pad being 25 shown in flat position. Fig. 2 is a perspective view showing the pad bent to circular form to inclose a bottle or like circular article. Fig. 3 is a detail sectional view of the 30 terminal portions of the pad showing the interlocking of the ends. Fig. 4 is a detail sectional view showing a modified form of interlocking terminal flap. Fig. 5 is a detail perspective view of the end portions of the pad showing a modified means for interlocking 35 the ends. Fig. 6 is an end view showing a modified form of pad embodying the invention. Fig. 7 is an end view of a pad more especially designed for use as a flat pad.

40 Referring more particularly to Figs. 1 to 3 of the drawings, my improved pad there shown comprises a series of parallel cushioning members made from a sheet or strip of flexible material (preferably stout 45 paper stock) that is bent or corrugated to form the walls 1, 2 and 3 of the members. The walls 1 comprise the outer side and the walls 2 form the inner side of the pad, and the walls 3 which connect the walls 1 and 50 2 are inclined preferably at an angle of about 60°, as this will be found a most effective position for the walls to resist crushing strain. Each of the cushioning members comprises two walls 3 connected by the walls 1 or 2.

When the pad is intended for the protec-

tion of bottles, jars or like articles having curved surfaces, the cushioning members comprising the walls or sides 1 will be slightly broader or wider than the cushioning members comprising the walls or sides 2, the result being that the sides or walls of the cushioning members abut upon at least one side of the pad while spaces are left between the walls 2 of the cushioning members at the opposite side of the pad. 60 By this means, the pad can be bent around the circular article to be protected and when thus bent, as illustrated in Fig. 2, the sides or walls 2 of the narrower cushioning members will be caused to also abut or approximately abut. A retaining strip 5 of flexible material is shown as affixed to the outer walls 1 of the pad so as to hold the various cushioning members in proper relative position and this retaining strip 5 may be of any desired width, covering either partially 65 or wholly the outer surface of the pad.

When the pad is to be used as a protective packing for a circular article, such as a bottle 80 or the like, the ends of the pad will be brought together around such article and will be fastened, preferably by means of one or more interlocking tongues or flaps at one end of the pad suitably engaging with the 85 opposite end of the pad. As shown in Fig. 1, the pad has two tongues or flaps 6 that are preferably notched or cut away as at 7 adjacent their inner ends. When the pad has been bent to circular form, the tongues 6 90 will be inserted as at 8 between the abutting edges of the walls 1, 1 at each side of the retaining strip 5. The flexibility of the pad will permit the notched portions 7 of the tongues to be slipped under the retaining 95 strip 5 at the points 9. The terminal wall adjacent the points 9 will set beneath the corresponding terminal wall adjacent the flaps 6 when the tongues 6 have been inserted in position for use, as indicated in 100 Fig. 2 of the drawings.

Instead of forming the flaps or tongues 6 integral with the walls of the cushioning members, these flaps might be formed separate and affixed to the terminal portion of the pad. So also, instead of the tongues or flaps being of the precise shape shown, they may be varied. Thus, in Figs. 4 and 5 the flap 6a which is shown at one end of the pad has two projecting ends and these ends will be bent inward and inserted in the transverse slots 11 that will be formed in the outer wall 105 110

1 of the terminal cushioning member at the opposite end of the pad. When the pad has been bent to circular form and the ends of the tongue 6^a have been forced into the slots 5 11, their resiliency will spread and interlock them with the wall of the pad. It is obvious that the precise construction of interlocking tongue may be varied without departing from the spirit of the invention.

10 In the preferred form of the invention above described, the cushioning members of my improved pad are of triangular outline with the walls 3 approximately (although not exactly) equal in width to the walls 1 and 2 15 and the walls 3 are at such an inclination that they will most effectively resist any crushing strains thrown upon them. Inasmuch as the walls of the cushioning members contact upon one side at least of the pad, it follows that any pressure exerted upon such 20 side of the pad will be distributed to the various cushioning members, thus not only giving greater resiliency to the pad but more effectively guarding against crushing the 25 pad at the point at which the pressure is applied. When the pad is bent to circular form to receive the article to be protected, the cushioning members should abut or approximately abut not merely at the outer 30 side but also at the inner side of the pad thus increasing the strength and efficiency of the pad. And it will be readily understood that the spaces between the edges of the cushioning members upon the inner side 35 of the pad will be greater or less according to the curvature of the articles for which the pad is adapted.

Where my improved pad is intended for the packing of flat articles or in situations in 40 which any considerable bending of the pad is not required, the cushioning members may be formed so as to abut at both their inner and outer edges as shown in Fig. 7 of the drawing. In this form of the invention, the 45 walls 1 and 2 of the pad are of the same width. If desired, retaining strips 5 and 5^a may be employed upon both sides of this form of the pad, as shown in the drawings.

While in the form of the invention above 50 described the cushioning members have a triangular shape in cross section, it is not essential that this precise shape be employed. Thus, for example, in Fig. 6 of the drawing, the pad is shown as comprising a series of 55 cushioning members, the inner and outer walls 1^a and 2^a of which are curved, the connecting walls 3^a being also shown as somewhat curved. In this form of the invention the edges of the cushioning members at the

outer side of the pad abut against each other, 60 while the edges at the inner side of the pad are separated sufficiently to permit the pad to be bent around the curved article, such as a bottle, jar or the like.

It is obvious that the precise details above 65 described may be varied without departure from the spirit of the invention, and that features of the invention may be employed without its adoption as an entirety.

Having thus described my invention what 70 I claim as new and desire to secure by Letters Patent is:

1. A packing pad comprising a strip of stout flexible material bent or corrugated to form a series of cushioning members which 75 are arranged in contact on at least one side of the pad.

2. A packing pad comprising a strip of flexible material bent or corrugated to form a series of cushioning members which are 80 arranged in contact at the outer side of the pad and are slightly spaced apart at the opposite side of the pad to permit said pad to be bent about the article to be protected.

3. A packing pad comprising a strip of stout flexible material bent or corrugated to form a series of cushioning members which are arranged in contact on at least one side of the pad, and a sheet of flexible material 85 extending across and joining the cushioning 90 members of the pad.

4. A packing pad comprising a strip of stout paper stock bent or corrugated to form a series of cushioning members which are arranged in contact on at least one side of 95 the pad, said pad being provided at one end with a flexible flap arranged to interlock with the opposite terminal of the pad.

5. A packing pad comprising a strip of stout flexible material bent or corrugated to 100 form a series of cushioning members which are arranged in contact on at least one side of the pad, one end of said pad being provided with laterally projecting tongues and the other end of said pad being provided 105 with slots or openings to receive said tongues.

6. A packing pad comprising a continuous strip of stout paper stock bent or corrugated to form a series of parallel tubular cushioning members triangular in cross section, the outer 110 walls of said members being broader than their inner walls, the edges of said cushioning members substantially abutting at one side of the strip.

LOUIS F. FLIPSE.
